UNITED STATES PATENT OFFICE.

JOHN HARVEY WYCKOFF, OF RARITAN, NEW JERSEY.

DESIGN FOR A RADIO LOUD SPEAKER.

Application filed April 21, 1926. Serial No. 17,364. Term of patent 3½ years.

To all whom it may concern:

Be it known that I, JOHN HARVEY WYCKOFF, a citizen of the United States, residing at Raritan, in the county of Somerset and State of New Jersey, have invented a new, original, and ornamental Design for Radio Loud Speaker, of which the following is a specification, reference being had to the accompanying drawing, forming part thereof.

In the drawings, Fig. 1 shows a view in

elevation, of a radio loud speaker, showing my new design. Fig. 2 is a top plan view thereof.

I claim:

The ornamental design for a radio loud speaker as shown.

In testimony whereof I have hereunto set my hand on this 13th day of April A. D., 1926.

JOHN HARVEY WYCKOFF.
